(57) **CLAIM**

The ornamental design for a pull, as shown and described.

DESCRIPTION

FIG. 1 is a perspective view of a pull showing my new design;

FIG. 2 is a front elevational view thereof, the undisclosed bottom is not part of the claimed design;

FIG. 3 is a side view thereof, the opposite side being a mirror image of the side shown;

FIG. 4 is an end view thereof; and,

FIG. 5 is a transverse cross-sectional view thereof.
